UNITED STATES PATENT OFFICE.

EDWARD L. CHOTT, OF CHICAGO, ILLINOIS, ASSIGNOR OF ONE-HALF TO HUGO J. CHOTT,
OF CHICAGO, ILLINOIS.

SUCTION APPARATUS FOR DENTAL CASTING APPARATUS.

1,142,023.

Specification of Letters Patent.

Patented June 8, 1915.

Application filed November 15, 1912. Serial No. 731,508.

To all whom it may concern:

Be it known that I, EDWARD L. CHOTT, a citizen of the United States, and a resident of the city of Chicago, county of Cook and 5 State of Illinois, have invented certain new and useful Improvements in Suction Apparatus for Dental Casting Apparatus, of which the following is a specification.

My invention relates to improvements in 10 dental casting apparatus and has for its object the provision of a simple and effective apparatus for this purpose, a special object of the invention being to provide an apparatus of this character by means of 15 which the force exerted in forcing the molten metal into the mold or crucible may be readily varied and predetermined.

The invention consists in the combinations 20 and arrangements of parts hereinafter described and claimed.

The invention will be best understood by reference to the accompanying drawing forming a part of this specification, and in which,

25 Figure 1 is a side view of an apparatus embodying my invention, shown in position for use, Fig. 2, an enlarged vertical section of the apparatus, and Fig. 3, a top plan view of a flask or crucible support employed 30 in the apparatus.

The preferred form of construction as 35 illustrated in the drawing comprises an elongated cylinder 1 which may, if desired, be formed of an ordinary piece of steel tubing. This cylinder is provided with a longitudinal slot 2 in one side thereof and with locking or positioning notches 3 in one edge of said slot, as shown in Fig. 1. A pump piston 4 is arranged to reciprocate in 40 the upper portion of cylinder 1, said pump piston being pivotally connected to the upper end of another tube 5 by means of a pivot pin 6, as shown. A tension spring 7 is anchored at its upper end to pivot pin 6

45 and at its lower end to a transverse pin or rod 8 traversing the lower portion of cylinder 1, as shown. An operating handle 9 is secured to tube 5 by means of a threaded stem 10 which passes through slot 2 and is 50 adapted to engage in any of the notches 3.

Another operating handle 11 is secured to cylinder 1 to facilitate manipulations of handle 9 when cylinder 1 is not securely anchored in position. By this arrangement it will be observed that handle 9 may be employed to force piston 4 to different positions in cylinder 1, and that said piston may be readily locked in these different positions by engaging the stem 10 of handle 9 in the corresponding notch 3. Handle 9 is readily released from the corresponding notch 3 by rotating the same slightly, whereupon piston 4 will be caused to make a sudden operative stroke under the influence of the tension in spring 7, and the length of the stroke will 55 depend upon the particular notch 3 in which the handle was previously locked. By pivoting piston 4 to tube 5 the same is given a freedom to assume a proper position in tube 1, thus facilitating the packing of said 60 piston and rendering the packing thereof 65 very effective.

The upper end of cylinder 1 is closed by a threaded cap 12 which is provided with an upstanding threaded nipple 13, as shown. 75 A hollow flask or crucible support 14 is provided with a downwardly extending threaded nipple 15 which is detachably secured to nipple 13 by means of a threaded union 16, as will be readily understood. 80 The bottom of the interior of the support 14 is covered by a wire mesh straining plate 17 and a straining or filtering filling 18, which may be of cotton or other suitable material, is placed in support 14 for the purpose of 85 straining or filtering the air or other gas passing through support 14 and into the upper end of cylinder 1. Support 14 is provided with a removable top 19 threaded thereto and having a plurality of perforations 20 therein. This support is also provided with a plurality of positioning pins 21 adapted to position a flask or crucible 22 thereon and surrounding perforations 20.

By this arrangement it will be observed 95 that upon release of handle 9 and consequently of piston 4 the operative stroke of said piston will tend to cause a vacuum in the upper portion of cylinder 1 and thus tend to draw air into said cylinder through 100

flask 22, as is usual in machines of this character.

A suitable burner 23 of any usual or desired construction is supported in operative relation with flask or crucible 22 by means of a vertical rod 24 which is adjustably secured by means of a clamp 25 to a horizontal rod 26 which in turn is removably and adjustably secured to nipple 13 by means of 10 a clamp 27. As shown, the cylinder 1 is rigidly mounted in position by means of a bracket 28 which may be secured to a side wall or other suitable support.

In use handle 9 is first set in the proper 15 notch 3 which will depend upon the size and consistency of the mold employed and other conditions well known to those familiar with the use of such apparatus. Then, the usual flask or mold is placed in 20 position on support 14 and the metal designed for the filling melted in the usual manner by means of burner 23. When the metal has been properly melted, handle 9 is released by touching it with the hand or 25 knee, or otherwise, whereupon piston 4 will instantly make its operative stroke. This tends to create a vacuum in the upper portion of cylinder 1 and the molten metal will be drawn into the mold in the usual manner.

30 While I have illustrated and described the preferred form of construction for carrying my invention into effect this is capable of variation and modification without departing from the spirit of the invention. I, 35 therefore, do not wish to be limited to the precise details of construction set forth, but desire to avail myself of such variations and modifications as come within the scope of the appended claims.

40 Having described my invention what I claim as new and desire to secure by Letters Patent is:

1. In a casting apparatus the combination of a cylinder having a longitudinal slot in 45 one side, said slot being provided with a plurality of locking notches; a reciprocatory piston in said cylinder; a spring connected with said piston and adapted to cause an operative stroke thereof to tend to produce a vacuum in one end of said cylinder and a 50 handle connected with said piston and projecting through said slot, said handle being adapted to engage said notches to lock said piston in different positions and thus for different lengths of operative strokes, substantially as described.

2. In a casting apparatus the combination of a cylinder having a longitudinal slot in one side, said slot being provided with a plurality of locking notches; a reciprocatory and rotatable piston in said cylinder; a spring connected with said piston and adapted to cause an operative stroke thereof to

tend to produce a vacuum in one end of said cylinder; and a handle connected with said piston and projecting through said slot, said handle being adapted to engage said notches to lock said piston in different positions and thus for different lengths of operative strokes, substantially as described. 65

3. In a casting apparatus the combination of a cylinder having a longitudinal slot in one side, said slot being provided with a plurality of locking notches; a reciprocatory and rotatable piston in said cylinder; a tubular piston rod connected with said piston; a spring arranged in said piston rod, one end of said spring being connected with said piston and the other end being connected with said cylinder, and arranged to cause an operative stroke of said piston to tend to produce a vacuum in one end of said cylinder; and a handle connected with said piston and projecting through said slot, said handle being adapted to engage said notches to lock said piston in different positions and thus for different lengths of operative strokes, substantially as described. 70

4. A pump comprising a cylinder having a longitudinal slot in one side, said slot being provided with a plurality of locking notches; a reciprocatory piston in said cylinder; a spring connected with said piston and adapted to cause an operative stroke thereof to tend to produce a vacuum in one 90 end of said cylinder; and a handle connected with said piston and projecting from said slot, said handle being adapted to engage said notches to lock said piston in different positions and thus for different lengths of operative strokes, substantially as described. 95

5. A pump comprising a cylinder having a longitudinal slot in one side, said slot being provided with a plurality of locking notches; a reciprocatory and rotatable piston in said cylinder; a spring connected with said piston and adapted to cause an operative stroke thereof to tend to produce a vacuum in one end of said cylinder; and a handle connected with said piston and projecting through said slot, said handle being adapted to engage said notches to lock said piston in different positions and thus for different lengths of operative strokes, substantially as described. 105

6. A pump comprising a cylinder having a longitudinal slot in one side, said slot being provided with a plurality of locking notches; a reciprocatory and rotatable piston in said cylinder; a tubular piston rod connected with said piston; a spring arranged in said piston rod, one end of said spring being connected with said piston and the other end being connected with said cylinder, and arranged to cause an operative 120 stroke of said piston to tend to produce a 125

vacuum in one end of said cylinder; and a handle connected with said piston and projecting through said slot, said handle being adapted to engage said notches to lock said piston in different positions and thus for different lengths of operative strokes, substantially as described.

In testimony whereof I have signed my name to this specification in the presence of two subscribing witnesses.

EDWARD L. CHOTT.
